CLAIM

The ornamental design for a tubing component, as shown and described.

DESCRIPTION

FIG. 1 is a perspective view of a tubing component showing our new claimed design;

FIG. 2 is a front elevational view thereof;

FIG. 3 is a left-side elevational view thereof;

FIG. 4 is a right-side elevational view thereof;

FIG. 5 is a top plan view thereof, the bottom plan view being identical to the top plan view thereof; and,

FIG. 6 is a perspective view showing the tubing component with environmental structure.

The dot-dash broken lines, in FIGS. 1–5, depict portions of the tubing component that form no part of the claimed design. The even length broken lines, in FIG. 6, illustrate environmental structure and form no part of the claim.
